CLAIM

The ornamental design for an ocular injector, as shown and described.

DESCRIPTION

The patent or application file contains at least one drawing executed in color. Copies of this patent or patent application publication with color drawings will be provided by the Office upon request and payment of the necessary fee.

FIG. 1 is a top front isometric view of an ocular injector showing a first embodiment of the claimed design;

FIG. 2 is a bottom rear isometric view of the ocular injector of FIG. 1;

FIG. 3 is a left side view of the ocular injector of FIG. 1;

FIG. 4 is a front view of the ocular injector of FIG. 1;

FIG. 5 is right side view of the ocular injector of FIG. 1;

FIG. 6 is a rear view of the ocular injector of FIG. 1;

FIG. 7 is a top view of the ocular injector of FIG. 1;

FIG. 8 is a bottom view of the ocular injector of FIG. 1;

FIG. 9 is a top front isometric view of an ocular injector showing a second embodiment of the claimed design;

FIG. 10 is a bottom rear isometric view of the ocular injector of FIG. 9;

FIG. 11 is a left side view of the ocular injector of FIG. 9;

FIG. 12 is a front view of the ocular injector of FIG. 9;

FIG. 13 is right side view of the ocular injector of FIG. 9;

FIG. 14 is a rear view of the ocular injector of FIG. 9;

FIG. 15 is a top view of the ocular injector of FIG. 9;

FIG. 16 is a bottom view of the ocular injector of FIG. 9;

FIG. 17 is a top front isometric view of an ocular injector showing a third embodiment of the claimed design;

(Continued)

FIG. 18 is a bottom rear isometric view of the ocular injector of FIG. 17;
 FIG. 19 is a left side view of the ocular injector of FIG. 17;
 FIG. 20 is a front view of the ocular injector of FIG. 17;
 FIG. 21 is right side view of the ocular injector of FIG. 17;
 FIG. 22 is a rear view of the ocular injector of FIG. 17;
 FIG. 23 is a top view of the ocular injector of FIG. 17;
 FIG. 24 is a bottom view of the ocular injector of FIG. 17;
 FIG. 25 is a top front isometric view of an ocular injector showing a fourth embodiment of the claimed design;
 FIG. 26 is a bottom rear isometric view of the ocular injector of FIG. 25;
 FIG. 27 is a left side view of the ocular injector of FIG. 25;
 FIG. 28 is a front view of the ocular injector of FIG. 25;
 FIG. 29 is right side view of the ocular injector of FIG. 25;
 FIG. 30 is a rear view of the ocular injector of FIG. 25;
 FIG. 31 is a top view of the ocular injector of FIG. 25;
 FIG. 32 is a bottom view of the ocular injector of FIG. 25;
 FIG. 33 is a top front isometric view of an ocular injector showing a fifth embodiment of the claimed design;
 FIG. 34 is a bottom rear isometric view of the ocular injector of FIG. 33;
 FIG. 35 is a left side view of the ocular injector of FIG. 33;
 FIG. 36 is a front view of the ocular injector of FIG. 33;
 FIG. 37 is right side view of the ocular injector of FIG. 33;
 FIG. 38 is a rear view of the ocular injector of FIG. 33;
 FIG. 39 is a top view of the ocular injector of FIG. 33;
 FIG. 40 is a bottom view of the ocular injector of FIG. 33;
 FIG. 41 is a top front isometric view of an ocular injector showing a sixth embodiment of the claimed design;
 FIG. 42 is a bottom rear isometric view of the ocular injector of FIG. 41;
 FIG. 43 is a left side view of the ocular injector of FIG. 41;
 FIG. 44 is a front view of the ocular injector of FIG. 41;
 FIG. 45 is right side view of the ocular injector of FIG. 41;
 FIG. 46 is a rear view of the ocular injector of FIG. 41;
 FIG. 47 is a top view of the ocular injector of FIG. 41;
 FIG. 48 is a bottom view of the ocular injector of FIG. 41;
 FIG. 49 is a top front isometric view of an ocular injector showing a seventh embodiment of the claimed design;
 FIG. 50 is a bottom rear isometric view of the ocular injector of FIG. 49;
 FIG. 51 is a left side view of the ocular injector of FIG. 49;
 FIG. 52 is a front view of the ocular injector of FIG. 49;
 FIG. 53 is right side view of the ocular injector of FIG. 49;
 FIG. 54 is a rear view of the ocular injector of FIG. 49;
 FIG. 55 is a top view of the ocular injector of FIG. 49;
 FIG. 56 is a bottom view of the ocular injector of FIG. 49;
 FIG. 57 is a top front isometric view of an ocular injector showing an eighth embodiment of the claimed design;
 FIG. 58 is a bottom rear isometric view of the ocular injector of FIG. 57;
 FIG. 59 is a left side view of the ocular injector of FIG. 57;

FIG. 60 is a front view of the ocular injector of FIG. 57;
 FIG. 61 is right side view of the ocular injector of FIG. 57;
 FIG. 62 is a rear view of the ocular injector of FIG. 57;
 FIG. 63 is a top view of the ocular injector of FIG. 57; and,
 FIG. 64 is a bottom view of the ocular injector of FIG. 57. The broken lines in the figures show portions of the ocular injector that form no part of the claimed design. The dash-dot-dash lines in the figures shows boundaries of the claimed design and form no part of the claimed design.
